CLAIM

The ornamental design for a medical device for treatment of sleep disorders, as shown and described.

DESCRIPTION

FIG. 1 is a front, right perspective view of a medical device for treatment of sleep disorders;

FIG. 2 is a front, right perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is top plan view thereof; and,

FIG. 8 is a front, top side perspective view thereof.

The broken line showing of electrical ports, communication ports and tubing is for the purpose of illustrating environmental structure and forms no part of the claimed design.
